UNITED STATES PATENT OFFICE

2,650,383

TOOTHBRUSH WITH A FLEXIBLE HEAD

Louis R. Bressler, Southampton, Mass.

Application March 7, 1952, Serial No. 275,345

3 Claims. (Cl. 15—167)

1

This invention relates to improvements in toothbrushes and is directed more particularly to toothbrushes having relatively flexible bristle carrying sections.

The principal objects of this invention are the provision of a toothbrush wherein bristle carrying head sections are flexibly associated so that in brushing the teeth bristles conform to the contour of the teeth thereby entering the spaces between the teeth for proper cleaning action.

Heretofore toothbrushes have been made where the bristle supporting head has included a plurality of bristle carrying sections connected by metal springs for relative flexing of the sections. Such brushes have not been satisfactory and are objectionable for numerous reasons. There is a faulty bond between the metal spring and plastic of the head sections, and the metal is subject to corrosion, as well as subject to fatigue. Furthermore, the metal sets so as to rupture with normal use and the tufts of bristles are not properly secured in the sections because the securing means, usually comprising staples, may not extend into the plastic material to the required depth. That is, the staples cannot extend through the metal spring which results in inadequate bristle securement.

According to this invention, a toothbrush construction is provided having a head end which is formed by bristle sections flexibly connected by a non-metallic spring member formed from plastic such as nylon.

Such a construction overcomes the difficulties experienced with prior art brushes and has many advantages thereover in that the plastic spring member is adequately bonded to the bristle sections molded therearound, is resistant to corrosion, and has a much longer life than a metallic spring in that it is capable of many times the flexing movements of a metal spring and the staples may impinge or extend through the nylon spring thereby to more securely unite the bristle tufts with the head section.

All of the above objects I accomplish by means of such structure and relative arrangements of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and in the combination and arrangement of parts as will be

2

hereinafter more particularly pointed out in the claims hereunto annexed and more fully described and referred to in connection with the accompanying drawings wherein:

5 Figs. 1 and 2 are plan and side elevational views of a toothbrush embodying the novel features of the invention;

10 Figs. 3 and 4 are plan and edge views of the resilient member of the toothbrush shown in Figs. 1 and 2; and

Fig. 5 is a partial sectional elevational view through the toothbrush shown in Figs. 1 and 2.

Referring now to the drawings more in detail, the invention will be fully described.

15 A toothbrush is indicated generally by 2 and has a handle 4 and a bristle supporting head 6.

The head 6 of the toothbrush includes an outer end section 8, intermediate sections 10 and a handle section 12.

20 The toothbrush will preferably be formed from suitable plastic material by a molding operation and a longitudinal resilient flat spring-like member 14 will be molded in sections forming the head.

25 The member 14 for the molding operation will be placed in the mold as is common in molding operations and will be shaped to extend in and through the intermediate sections with its opposite ends extending into the sections 8 and 12.

30 The resilient member 14 according to the invention will be an elongated strip of plastic material such as nylon and will be relatively thin.

35 Said member 14 may have openings 16 in opposite ends thereof and will have notches 18 along opposite longitudinal edges thereof, more or less separating its length into sections 20, 22 and 24 corresponding to the sections 8, 10 and 12 of the toothbrush head 6.

40 The molding operation and arrangement of the member 14 will be such that the notches 18 will correspond with narrow transverse spaces 26 between the sections of the head. In this way the member 14 has a transverse width somewhat less than the adjacent sections 8, 10 and 12. These narrow portions between notches provide flexibility to the member 14 at the spaces between the head sections.

45 The member 14 being formed from such plastic material has great flexibility and strength so that the head sections are relatively movable.

50 As distinguished from a metallic member 14, the plastic provides greatly increased flexibility without rupture. A brush head incorporating a steel resilient member has a much shorter life than where the nylon member is used. From very

many tests on the same machine for flexing the head sections, steel resilient members have been found to set and rupture in 300,000 to 400,000 flexes while with the resilient members of this invention there have been no ruptures in 3,000,000 flexes.

Furthermore, the resilient member of this invention does not corrode during use of the toothbrush, there is no tendency for it to set from constant use and stapling may extend through the resilient member. With metallic resilient member stapling may not impinge or pass therethrough so that according to the invention it is possible to more securely fix the tufts of bristles in the head and the bond between the plastic resilient member is far superior to that possible between plastic and metal.

In some manufacturing procedures, sockets for bristle tufts are provided in the molding operation. In others, sockets are formed in the molded toothbrush.

The bristle tufts are secured in the sockets ordinarily by small wire staples which engage intermediate portions of the bristles and are driven or pressed into the plastic at the bottoms of the sockets.

According to this invention, sockets extending to the resilient member 14 may be provided in the molding operation or they may be formed by drilling the molded toothbrush and if desired the drilling may extend through the member 14 which would be impracticable were the resilient member made from spring metal.

Fig. 5 illustrates one form of staple 28 holding the bristles 30 of a tuft 32. This staple formed from small size wire extends through the resilient member 14 into the bristle sections and securely anchors the tuft in place.

It is stated that the resilient member may be formed from nylon. Nylon is the generic name for materials defined as synthetic fiber-forming polymeric amides having proteinlike chemical structure derived from coal, air and water, or other substances and characterized by extreme toughness and strength. Nylon has superior flexibility, possesses great strength, resists fatigue by flexing as well as corrosion, and bristle stapling may extend therethrough without impairing its desirable characteristics. It will be understood that plastic material not only includes nylon but other types of plastics which have the important characteristics mentioned.

The invention may be embodied in other specific forms without departing from the essential characteristics thereof. Hence, the present embodiments are therefore to be considered in

all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A brush construction of the type wherein bristle carrying sections are connected by a resilient member for relative flexing movements comprising in combination, opposite end sections and a plurality of intermediate sections therebetween of plastic material molded about an elongated relatively thin resilient member having opposite ends in said end sections and an intermediate portion extending through said plurality of intermediate sections, and tufts of bristles secured to said sections by staples extending through said resilient member and being anchored in the upper portions of said sections.

2. A brush construction as set forth in claim 1 wherein said resilient member is formed from nylon.

3. A toothbrush having a flexible head comprising, an elongated handle and a sectionalized head at one end thereof enclosing a resilient member, said head including an inner head section integral with an end of said handle and an outer head section and a plurality of intermediate head sections therebetween, said resilient member comprising a strip of resilient plastic having opposite ends disposed in the inner and outer head sections and having an intermediate portion extending through said intermediate sections, and transversely spaced rows of longitudinally spaced tufts of bristles secured to said sections by staples extending through said resilient member and being anchored in the upper portions of said sections.

LOUIS R. BRESSLER.
